(57) **CLAIM**

I claim the ornamental design for an infant support pillow, as shown and described.

DESCRIPTION

FIG. 1 is a top perspective view of an infant support pillow showing my design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a bottom plan view thereof.
